SEWING MACHINE ATTACHMENT

Osher Gosman, Vineland, N. J.

Application April 14, 1933. Serial No. 666,216

4 Claims. (Cl. 112—122)

This invention relates to sewing machines and more particularly to that type of sewing machine especially adapted for use in the making of belt accommodating loops for trousers.

5 In accordance with the present invention means is provided for ready attachment to such a type of machine for cutting the cloth from which the loops are made into a strip of the desired width thereby insuring the making of belt loops of uniform width.

Briefly the invention consists in the provision of a feeding device and a cutting device adapted to cooperate with the usual feeding device of the machine in a manner to insure the placing of the cloth under proper tension during the cutting operation.

Further the invention consists in the provision of a meter for attachment to the machine so that the operator may readily ascertain when a suitable length of the material has been cut and sewed for making a predetermined number of belt loops.

The invention together with its numerous objects and advantages will be best understood from a study of the following description taken 25 in connection with the accompanying drawings wherein:

Figure 1 is a top plan view of a sewing machine having the attachment applied thereto.

Figure 2 is a fragmentary plan view of a portion of the machine showing the attachment applied thereto and with certain parts of the machine removed.

Figure 3 is a view somewhat similar to Figure 2 with the base plate of the machine removed.

35 Figure 4 is a sectional view taken substantially on the line 4—4 of Figure 3.

Figure 5 is a side elevational view of a cam operated arm to be hereinafter more fully referred to.

40 Figure 6 is a fragmentary side elevational view of a feed device forming part of the invention, with certain parts broken away and shown in section.

Figure 7 is a bottom plan view of the tooth equipped head of the feed device.

Figure 8 is a side elevational view thereof.

Figure 9 is a plan view of a portion of the usual cam shaft.

50 Figure 10 is a sectional view taken substantially on the line 10—10 of Figure 9.

Figure 11 is a sectional view taken substantially on the line 11—11 of Figure 2.

Figure 12 is a perspective view of the knife blade.

Figure 13 is a side elevational view of the cloth guide.

Figure 14 is a plan view of a portion of the cloth showing a part thereof folded and stitched as is customary in the making of loops, and another portion thereof slit in accordance with the present invention.

Figure 15 is a transverse sectional view taken substantially on the line 15—15 of Figure 14.

Figure 16 is a fragmentary sectional elevational view showing the meter as applied to the machine.

Referring to the drawings by reference numerals, reference will be had particularly only to those parts of the conventional sewing machine with which the invention is concerned. In this connection it will be seen that the sewing machine designated generally by the reference character 10 includes among parts the base plate 11, the cloth guiding and folding member 12, 75 pressure foot 13, the feed member 14 for feeding the cloth through the machine and beneath the presser foot 13, arm 15 carrying the feed member 14, shaft 16 suitably journaled in bearing ears provided therefore at the rear edge of the base 80 plate 11, the plate 17 pivotally connected with the shaft 16 and provided at its upper edge with bearing sleeves 18 in which are fixed the ends of a shaft 19 and to which shaft is pivoted one end of the feed arm 15. In addition the sewing 85 machine is equipped with the usual drive shaft 20 that, as is conventional, is provided with the cam 21 with which the arm 15 is engaged in the usual manner for actuating the arm to feed the cloth through the guide and to the needles of 90 the machine in a well known manner.

The sewing machine as above described is a conventional and well known type of machine especially adapted for sewing strips of cloth in the making of belt loops and is not of the essence 95 of the invention. In using this type of machine it is first necessary to cut the cloth into strips of desired width and this is usually accomplished by hand with the result that the strips are not always of uniform width.

To overcome this it is now proposed, in accordance with the present invention to provide for the cutting of cloth of any width within reason into a strip of the proper width as the cloth is being fed to the machine. To this end then 105 the invention consists in the provision of a device to cooperate with the conventional cloth feeding device 14 in exerting sufficient tension on the cloth as it is being fed to the machine and thereby insure a neat and efficient cutting 110

or slitting of the cloth into a strip of the desired width. This auxiliary feed device comprises an arm 22 which at one end is provided with an eye or sleeve 23 for pivotally engaging the arm with the pivot shaft 19 as suggested in Figure 4. Adjacent its free end the arm 22 is provided with a depending lug 24 to which is secured one end of a strip 25 of metal or other suitable material that has its free end paralleling the free end portion of the arm 22 as shown in Figure 5. The free end of the arm 22 and the free end of the strip 25 are adapted to straddle a cam 26 provided on the shaft 20 in accordance with the present invention and disposed at the proper angular relation with respect to the cam 21. An arcuate arm 27 is secured at one end as at 28 to the free end of the arm 22 and this arm 27 is divided adjacent its fixed end into two sections pivotally connected as at 29. A suitable spring 30 engages the convex edge of the arm 27 and bridges the joint between the sections of the arm in a manner to normally urge the free section of the arm downwardly and in alignment with the fixed section of the arm. At one end the spring 30 is anchored as at 31 to the fixed section of the arm 27.

At its free end the arm 27 is provided with a tooth equipped head disposed in advance of the cloth feeding device 14 and in substantial alignment with the said cloth feeding device 14 to engage the top face of the cloth and thereby cooperate with the feeding device 14 for feeding the cloth through the machine and at the same time place a desired tension upon the cloth during the actual slitting or cutting operation. The said head on the arm 27 is designated by the reference numeral 32 and as clearly shown in Figures 7 and 8 comprises a body plate that is bolted or otherwise secured to the free end of the arm 27 and is equipped with laterally spaced relatively short toothed bars 33 and a relatively elongated intermediate toothed bar 34.

The cutting device includes an arm 35 that at one end is provided with an eye or sleeve 36 for pivotal engagement with the shaft 16 as shown in Figure 4. At its free end the arm 35 extends upwardly and forwardly as at 37 and cooperates with the free end of a strip 38 secured to an intermediate portion of the arm 35 to straddle a third cam 39 provided on the shaft 20 and disposed at the same angle as the cam 21 with reference to the cam 26.

To the free end 37 of the arm 35 there is secured one end of an angular arm 40, said one end of the arm being anchored to the end 37 of arm 35 as at 41. The free end of the arm 40 is provided with bolt and nut means 42 for engaging the slotted end of a knife blade 43 for securing the blade 43 at the desired vertical adjustment on the arm 40. The free end of the arm 40 terminates adjacent the free end of the aforementioned arm 27 for supporting the knife 43 in a manner to cooperate with a knife blade 44 embedded in the inner side of the combined guide and folding member 12 as will be clear from a study of Figure 11.

As shown in Figure 3 the arm 22 is normally urged toward the arm 15 through the medium of a spring 45 disposed about the shaft 19 and bearing against the proximate end of the arm 22.

As is also conventional, the plate 17 is caused to rock back and forth, motion being transmitted thereto from the cam shaft 20 through the medium of a disk 46 provided on one end of the shaft and having eccentrically connected thereto

an arm 47 which is pivotally connected to an arm 48 extending from one end of the plate 17 as will be clear from a study of Figure 3.

In operation the cloth 45 of any suitable length and width is fed through the machine passing through the combined guide and folding member 12. Obviously in the feeding of the cloth the arm 15 carrying the cloth engaging and feeding member 14 is caused to oscillate, and upon its forward and upward movement engages the under side of the cloth to draw the cloth through the machine as the arm 15 moves rearwardly and downwardly. In this connection it will be noted that the arm 22 through the medium of the cam connection between the arm and the shaft 20 and the rocking movement of the plate 17 has a movement substantially similar to the arm 15 with a result, that as the member 14 associated with the arm 15 moves up to engage the under side of the cloth, the arm 22 moves downwardly and forwardly so that the toothed bars 33, 34 engage the top side of the cloth in advance of the member 14 and at about the same time that the member 14 engages the under side of the cloth. Similarly the arm 22 and its associated parts rise and move rearwardly at substantially the same time that the arm 15 and its associated parts lower and move rearwardly thus releasing the cloth completing the cycle of operation.

The arm 35 through the medium of the cam connection between said arm 35 and shaft 20 will of course have only a rocking movement giving a vertical up and down movement to the knife 43, the knife 43 moving downwardly and cutting the cloth as the toothed equipped elements 32 and 105 14 engage the cloth and draw it forwardly through the machine. Upon release of the cloth by the tooth equipped elements 14 and 32 the movement of the knife 43 is upwardly so that it will be seen that during each actual cutting stroke 110 of the knife the cloth is under sufficient tension to insure a smooth cutting operation and a cutting 115 of the cloth 45 into a uniform strip.

There is also provided on one side of the guide 12 in accordance with the present invention a 120 combined shield and deflector 49 against which the unused portion 45a of the cloth is directed as the feeding and cutting of the cloth takes place. Shield 49 serves to guide the unused portion 45a of the cloth outwardly and downwardly 125 so as not to interfere with either the feeding or cutting operation.

As is well known, and as clearly shown in Figures 14 and 15 as the cloth passes through the combined guide and folding member 12 the cloth 130 is folded in a manner clearly shown in Figure 15 and the folded and stitched portion of the cloth is then cut at intervals into relatively short strips of suitable length for use as belt loops of the type that are usually stitched onto the waist 135 of trousers for accommodating a supporting belt.

To insure positive and efficient cooperation between the fixed knife blade 44 and the knife blade 43 there is provided a spring tension device engaging one side of the arm 40 for urging the 140 arm in the direction of the arm 27. Such spring tension device in the present instance, and as shown in Figures 1 and 2 consists of a standard 50 rising from the plate 11 and having swivelly connected with its upper end an adjusting screw 145 51 having screw threadedly engaged therewith a nut 52. Extending laterally from the arm 40 is a pin 53 and a coil spring 54 has one end disposed about the pin 53 and abutting the arm 40, while the other end of the spring is disposed 150

- about the screw 51 and seats against the nut 52. Obviously by screwing the nut 52 relative to the screw 51 in the desired direction tension of the spring 54 may be adjusted as found desirable.
- 5 In accordance with the present invention there is also provided a meter designated generally by the reference numeral 55 and this meter is for the purpose of enabling the operator to determine when a suitable length of cloth has been folded and stitched and as would be necessary for making a predetermined number of belt loops. In the present instance I have shown the meter 55 having a driving connection with the shaft 20 through the medium of gearing 56 and a universal connection designated generally by the reference numeral 57 and of a well known type. The details of the meter structure are not of the essence of the present invention and in the present instance the meter 55 is somewhat similar to a speedometer of a known type and is so adjusted that the meter reading will change one digit when a predetermined length of the cloth has been folded and stitched into strip form. Thus for example assuming that to make twenty four belt loops it would require a strip twenty seven inches long, the meter would be so set that when approximately twenty seven inches of the cloth has been folded and stitched into proper strip form the meter reading will change one digit, and obviously when the reading so changes the operator then is visually informed that a sufficient portion of the cloth has been folded and stitched into a strip of the required length.
- While I have herein shown and described the preferred embodiment of the invention it is to be understood that it is in nowise intended to restrict the invention to the precise details, combination, construction and arrangement of elements as shown and described other than may be necessary to teach the requirements of the prior art and scope of the appended claims.
- Having thus described my invention, what I claim as new is:
1. A sewing machine including in combination, a presser foot, a pivot shaft, a plate connected with the pivot shaft, a shaft carried by the pivot plate, a cam equipped shaft, an operating connection between said cam equipped shaft and said plate for rocking the latter upon rotation of the cam equipped shaft, a feeding in finger arranged to engage the under side of the fabric for feeding the fabric forwardly beneath the presser foot, a rocker arm supporting said finger pivotally connected with the plate supported shaft and being also provided intermediate its ends with means for engaging a cam on the cam shaft, a second feeding in finger disposed forwardly of the first named feeding in finger and arranged to engage the top face of the fabric and to cooperate with the first named feeding in finger for feeding the cloth forward beneath the presser foot, a rocker arm for the second named feeding in finger pivotally connected with the plate carried shaft, means on the rocker arm of the second named feeding in finger for engaging a second cam on said cam shaft, a rocker arm pivotally connected at one end to said pivot shaft, means on the last named rocker arm engaging a third cam on said cam shaft, a knife carrying member secured to the last named rocker arm, and a knife carried by said knife carrying member for severing the fabric lengthwise thereof as it is fed forward beneath the presser foot.
2. A sewing machine including in combination a presser foot, a combined guide and folding member for guiding and folding the fabric as it is fed beneath the presser foot, a pivot shaft, a plate connected with the pivot shaft, a shaft carried by said plate, a cam equipped shaft, an operating connection between the cam equipped shaft and the plate for rocking the latter upon rotation of the cam equipped shaft, a feeding in finger arranged in operative position to the combined guide and folding member to engage the under side of the fabric for feeding the fabric through said member, a rocker arm supporting said finger and pivotally connected with the plate supported shaft, said rocker arm being also provided intermediate its ends with means for engaging a cam on the cam shaft, a second feeding in finger disposed forwardly of the first named feeding in finger and arranged to engage the top face of the fabric to cooperate with the first named feeding in finger for feeding the cloth, a rocker arm for the second named feeding in finger pivotally connected with the plate carried shaft, means on the rocker arm of the second named feeding in finger for engaging a second cam on said cam shaft, a rocker arm pivotally connected at one end to said pivot shaft, means on the last named rocker arm for engaging a third cam on said cam shaft, and a cutting device carried by the last named rocker arm for severing the fabric lengthwise thereof as it passes through said combined guide and folding member.
3. A sewing machine including in combination a cam shaft, a pivot shaft mounted rearwardly of the cam shaft and parallel thereto, a plate connected with the pivot shaft, an operating connection between the cam shaft and the plate for rocking the latter upon rotation of the cam shaft, a pair of spaced rocker arms pivotally connected at one end with said plate, a pair of cams on the cam shaft, means on each of said rocker arms for engaging one of said cams, a feeding in finger mounted on one of said rocker arms, a second feeding in finger mounted on the other of said rocker arms in advance of the first named feeding in finger and cooperable therewith for feeding cloth through the sewing machine and for exerting a tension on the cloth during the feeding thereof, a rocker arm pivotally connected at one end with the pivot shaft, a third cam on the cam shaft, means on the last named rocker arm engaging said third cam, and a trimming device carried by the last named rocker arm in proximity to the second named feeding in finger for severing the cloth as it is fed through the machine.
4. A sewing machine including in combination a folder for guiding and folding a strip as it is fed through the sewing machine, a trimming mechanism operating laterally of the folder and including a knife movable relative to the folder, a fixed knife blade on one edge of the folder cooperating with the first mentioned knife for trimming the strip to predetermined width as it passes through the folder, and a combined shield and deflector mounted on the folder at the same side thereof with the knife blade for directing the severed portion of the strip outwardly and downwardly as the trimmed portion of the strip passes through the folder.

OSHER GOSMAN.
